UNITED STATES PATENT OFFICE

HERBERT H. HILLMAN, OF GRAND HAVEN, MICHIGAN, ASSIGNOR TO CHALLENGE REFRIGERATOR COMPANY, OF GRAND HAVEN, MICHIGAN, A CORPORATION OF MICHIGAN

REFRIGERATOR AND THE LIKE

Application filed September 17, 1927. Serial No. 220,228.

The present invention relates to refrigerators and the like; and its object is, generally to provide an improved refrigerator construction, and more particularly an improved metallic casing for the wooden frame of the refrigerator and improved means for securing such casing to the frame.

This and any other and more specific objects hereinafter appearing are attained by, 10 and the invention finds preferable embodiment in the structure hereinafter particularly described in the body of this specification and illustrated by the accompanying drawings, in which:

15 Figure 1 is a view in perspective of a refrigerator;

Figure 2 is an inner side view of one of the door closures thereof;

20 Figure 3 is a sectional view of said closure taken on either line 3—3 of Figure 2;

Figure 4 is another sectional view of said closure taken on any line 4—4 of Figure 2;

25 Figure 5 is a top plan view of the refrigerator, the top casing member being removed;

Figure 6 is a view in perspective of said top casing member, showing its inner or under side;

30 Figure 7 is a vertical sectional view of the upper portion of the refrigerator taken on line 7—7 of Figure 1; and

Figure 8 is a vertical sectional view of casing members of the refrigerator taken on line 8—8 of Figure 1.

In the embodiment of the invention illustrated by these drawings, the refrigerator has a wooden body, box or frame comprising a top 1, back 2, sides 3, bottom 4, and front 5 provided with door openings closable by closures 6, 7, 8 hingedly mounted at 9, 10, 11 respectively and having wooden bodies or frames, as the body 12 of closure 6. These wooden bodies or frames of said box (excepting for its back and bottom) and of said closures are on their outer surfaces overlaid and concealed, ornamented and protected by metallic sheet casing members formed and secured to said wooden bodies or frames in the following manner:

50 The sides 3 of the refrigerator's wooden box are covered or overlaid by casing mem-

bers 13 having rear inwardly extending flanges 14 secured to the back 2 of the refrigerator wooden body as by screws 15 passing through holes 16 in said flanges. These casing members 13 have inwardly offset upper edge portions 17 and inwardly offset forward edge portions 18—all as seen in Figures 8 and 5. The front casing member 19 enclosing the front 5 of the wooden body or frame of the refrigerator box has inwardly (or rearwardly) extending flanges, as the flange 20 in Figure 7, engaging in the rabbets, as the rabbet 21 seen in said view, of the door openings. Said casing member 19 has also an inwardly offset upper edge portion 22 as seen in Figures 5 and 7, and rearwardly extending vertical flanges 23 engaging the inwardly offset vertical front edge portions 18 of the side casing members 13.

The top casing member 24 covering the top 1 of the refrigerator wooden box or frame has a downwardly extending peripheral flange 25 and is provided adjacent its forward edge with inwardly or rearwardly extending lugs or catches 26 engaging beneath a forwardly extending ledge or keeper 27 secured as by screws to the upper surface of the wooden top 1, as seen in Figure 7. This peripheral flange 25 engages the inwardly offset upper edge portions 22 of the front casing member 19 and 17 of the casing members 13, and also the rear edge of the wooden top 1 to which it is secured as by screws 28 passing through holes 29 in the flange 25.

The wooden bodies or frames of the door closures 6, 7, 8 are covered and concealed by closure casing members 30, 31, 32 respectively. These casing members, as for example the casing member 30 for closure 6, are each provided with an inwardly extending peripheral flange 33 surrounding the wooden body of the closure, such flange having at the free or outward corners of the closure an overhanging portion 34 underneath which said corners are received as particularly well seen in Figures 2 and 3. These closure members 30, 31, 32 are secured in place by the screws 35 which serve to mount the hinges 36, 37, 38 on the closures, such screws passing through holes in such hinges and in these closure

members and being threaded in the wooden closure frames.

The side casing members 13 are first secured to the wooden box or frame of the refrigerator by inserting and screwing down the screws 15. The front closure member 19 is then applied to the wooden frame, its flanges 23 covering the inwardly offset side edge portions 18 of the side casing members 17, and said front member 19 is secured in place by screws 39 passing through holes in the hinges 36, 37, 38 to mount the same and through holes in the front member 19 and threaded into the wooden box or frame of the refrigerator. The top casing member 24 is then applied, its catch 26 engaging under the ledge or keeper 27 and its flange 25 covering the inwardly offset top edge portions 17 of the side casing members 13 and 22 of the front casing member 19, and the screws 28 are inserted to secure said flange 25 at the rear of the refrigerator.

It will thus be seen that all the casing members are readily applied to the wooden bodies or frames of the refrigerator and its closures, and are secured in place merely by the screws which serve to mount the closures' hinges and by screws which are not visible at the top, sides or front of the refrigerator.

The invention being intended to be pointed out in the claims, is not to be limited to or by details of construction of the particular embodiment thereof illustrated by the drawings or hereinbefore described.

I claim:

1. In a structure of the character described: a body having a front, a back, opposite sides and a top provided with a keeper; side casing members having inwardly offset top edge and front edge portions and rear flanges secured to said back; a front casing member having an inwardly offset top edge portion and lateral rearwardly extending flanges engaging the inwardly offset front edge portions of the side casing members; a top casing member having, on its under side and within its hereinafter-mentioned flange, a catch engaging the keeper and a downwardly extending flange engaging the inwardly offset top edge portions of the side casing members and of the front casing member, and secured to said back.

2. In a structure of the character described: a body having a front provided with a door opening, a back, opposite sides and a top provided with a keeper; side casing members having inwardly offset top edge and front edge portions and rear flanges secured to said back; a front casing member having inwardly extending flanges engaging the sides of the door opening, an inwardly offset top edge portion and lateral rearwardly extending flanges engaging the inwardly offset front edge portions of the side casing members; a top casing member having, on its un-

der side and within its hereinafter-mentioned flange, a catch engaging the keeper and a downwardly extending flange engaging the inwardly offset top edge portions of the side casing members and of the front casing member, and secured to said back. 70

3. In a structure of the character described: a body having a front, a back, opposite sides and a top provided with a keeper; side casing members having inwardly offset top edge and front edge portions and rear flanges secured to said back; a front casing member having an inwardly offset top edge portion and lateral rearwardly extending flanges engaging the inwardly offset front edge portions of the side casing members; a top casing member having, on its under side and within its hereinafter-mentioned flange, a catch engaging the keeper and a downwardly extending flange engaging the inwardly offset top edge portions of the side casing members and of the front casing member. 80

4. In a structure of the character described: a body having a front; a back, opposite sides and a top provided with a keeper; side casing members having rear flanges secured to said back; a front casing member having lateral rearwardly extending flanges engaging the front edge portions of the side casing members; a top casing member having, on its under side and within its hereinafter-mentioned flange, a catch engaging the keeper and a downwardly extending flange engaging the top edge portions of the side casing members and of the front casing member, and secured to said back. 90

In testimony whereof I have hereunto set my hand at Grand Rapids, Michigan, this 14th day of September, 1927.

HERBERT H. HILLMAN.
